[57] CLAIM

The ornamental design for a loose leaf binder, as shown and described.

DESCRIPTION

FIG. 1 is a front perspective view of a looseleaf binder showing my new design;

FIG. 2 is a front elevational view thereof;

FIG. 3 is a top plan view thereof, the undisclosed bottom being substantially the same;

FIG. 4 is a left side elevational view thereof;

FIG. 5 is a right side elevational view thereof;

FIG. 6 is a rear elevational view thereof; and

FIG. 7 is a front elevational view thereof, in a fully opened position.
